UNITED STATES PATENT OFFICE.

AMOS R. GARBER, OF MOUNT JOY, PENNSYLVANIA, ASSIGNOR OF ONE-HALF TO
ERNEST K. POST, OF MEDIA, PENNSYLVANIA.

SWITCH THROWING AND LOCKING MECHANISM.

1,079,120.

Specification of Letters Patent. Patented Nov. 18, 1913.

Application filed March 10, 1910. Serial No. 548,423.

To all whom it may concern:

Be it known that I, AMOS R. GARBER, a citizen of the United States, and a resident of Mount Joy, in the county of Lancaster, Pennsylvania, have invented certain new and useful Switch Throwing and Locking Mechanism, of which the following is a specification.

My invention relates to switch throwing and locking mechanism of the type intended to be unlocked, thrown, and locked by the movement of a single rod.

The purpose of my invention is, to distribute locking, throwing and unlocking strains to the best advantage so as to obtain a minimum of resistance.

A further purpose of my invention is to shift the switch-operating rod laterally into locking engagement with a fixed surface at the end of its stroke and to retain it therein by reason of further movement of the driving plate.

A further purpose of my invention is, to overcome the objectionable characteristics of cam switch operation and of bell cranks and throwing structures, which change the direction of movement, avoiding the expense of the parts themselves, the additional resistance imposed by them, and the additional exposure to injury caused by their presence.

A further purpose of my invention is to hold the switch free from the driving plate while setting and releasing the usual switch lock.

A further purpose of my invention is to provide a lock for the switch-operating rod itself, which lock shall be supported free from the driving plate.

A further purpose of my invention is, to brace the switch against fixed parts at each end of the switch movement, not only rigidly holding the switch by this additional means, but relieving the locking and unlocking operations of all friction therefrom. The saving in labor is attended also by greater reliability in making the indication contacts.

A further purpose of my invention is, to rigidly join the cross connection from the pipe line to the switch operating rod during the switch throwing operation and to release it therefrom at each end of said operation, shifting the strain of the switch to fixed

members at approximately the same time as but preferably slightly prior to the beginning of movement of the slide bar of the locking mechanism.

Further purposes of my invention will appear throughout the specification and claims attached hereto.

I have illustrated one form of my invention which is durable, of good mechanical construction and well illustrates the invention, but recognize that many other forms thereof may be made use of, coming within the spirit and scope of my invention, and therefore present the illustrations and descriptions of this form as illustrative only.

Figure 1 is a top plan view of a track structure to which my invention is applied, the hand lever being shown in elevation. Fig. 2 is a top plan view of the preferred form of my construction shown in Fig. 1 with top plate removed. Fig. 3 is a section on line 3-3 of the structure shown in Fig. 2. Fig. 4 is a section upon line 4-4 of Fig. 3. Fig. 5 is an elevation of a part of Fig. 2.

1 designates the track rails adjoining a switch whose points 2, 3 are to be moved, for the purpose of throwing the switch, by means of rod 4 pivotally connected to the points by brackets 5 and pivots 6. The lock rod 7 is connected to the switch points by rods 8 and 9, capable of adjustment by turnbuckle 10.

For the support of the operating mechanism the ties 11 are preferably extended to provide bearing for a base plate 12 secured thereto in any suitable manner as at 13 and supporting a pillow plate at 14. I have illustrated the ties as rigidly held in position at their opposite ends by strip 15 in any suitable manner and have shown a spacing bar 16 pivotally connected to the switch points by brackets 17 and pivots 18 to complete the illustration. I have also illustrated, at 19, the means by which, at the present time, the positions of the locking grooves or notches in the locking rod are adjusted, and the rod 20 is provided with blocks or other parts 21 to enter the notches at the limits of the movement of the switch to lock it in position.

In Fig. 1, I have shown the hand lever 22, latch lever 23, and segment 24, and have shown the lever as pivoted at 25 in the usual

manner and connected as at 26, to throw rod 27 for the unlocking, throwing and locking of the switch.

The structure thus far described, as well as the bell crank 28 pivoted at 29, by which transverse movement is given to a rod, are all well known in the art.

My invention contemplates new and useful connections between a transverse driving rod as 30, the switch rod 31, which I will here call the switch rod or switch-operating rod, and the slide bar 20 of the locking system, or parts having similar functions, by which the switch may be thrown by direct movement, with previous unlocking and subsequent locking movement of the bar 20. I show a structure by which the mechanism for this operation may be thrown without change of direction of the movement of the switch parts from the direction of movement of the driving rod 30, and with advantageous distribution of the strains so that the throwing and locking operations shall be free from frictional binding interference with each other and there shall be substantially no side strains upon the operating mechanism. I particularly desire to avoid the necessity for cam engaging surfaces for the switch throwing movement.

In order to provide a good mechanical frame structure for the fixed and movable parts of my operating mechanism, I prefer to make the relatively fixed and movable parts in the form of frames comprising spaced plates united with the requisite rigidity and having the guiding slots therein in duplicate, thus equalizing the strains and avoiding diagonal strains.

Because I prefer to mount and have shown the whole structure as mounted upon the base plate I will first refer to the locking bar and to its mounting for movement through the guiding and supporting means. This bar is well known. I have mounted it upon the block 32 within which studs 34 are secured. Above the base these studs afford bearing for rollers 35, which are maintained free to turn by the bodies 36 of the studs which extend above them and support the plates 37 held in place by nuts 38. The slide bar is shown as made up of two plates 39 and 40 which are spaced by means of a sleeve 41 and rivets 42.

Continuing my illustration: For various purposes of causing movement of the slide bar with movement of driving rod 30 I provide a frame, preferably made up of plates, as 43 and 44, which are spaced and secured together by any desired means. I have chosen a rivet 45 for this purpose at one end and have accomplished the same purpose at the opposite end by a head 46 which lies between the plates and is riveted thereto at 47 at the end to which the driving rod 30 is to be attached. Attachment is made by

any suitable yoke engaging with the end 48 so that movement of the driving rod 30 shall cause movement of the frame comprising plates 43 and 44. I guide this movement by means of rollers 49 at the sides of the plates, 70 and secure the rollers 49 upon the studs 50 which space plates 51 and 52 and which are secured at one end both to the plate 52 and to the support at 53 and at the other end to the upper plate 51 and cover plate 54 by 75 nuts 55.

It will be evident that the so-called "fixed" members of the relatively fixed and movable coöperating members are best constructed in the form of frames, one embracing the other to distribute the contact and balance the structure, though their functions can be performed by other constructions and arrangements. To effect the locking function, the faces with which rod 31 or any member upon it engages at the end of its stroke must be fixed against transverse movement. Where I have referred to this member as "fixed" or "transversely fixed" I wish to be understood as indicating such immovability transversely 90 during the periods of rest of the rod 31 as shall effectively prevent transverse movement of this rod.

In the form shown, the top and bottom plates 51 and 52 are grooved or slotted in duplicate in the direction of the length of the slide bar, as at 56, to guide the ends 57 of the pin passing through the spacing sleeve 41 so that the slide bar can have longitudinal movement only and shall be limited by these slots 56 to the requisite ultimate position in each direction to perform locking function. As illustrated, the portions 58 of the pin 57 lie within duplicate slots 59 in the plates 43 and 44, respectively, which slots comprise intermediate straight portions 60 and reversely turned cam end slots 61 and 62, with the result that movement of plates 43 and 44 in their only possible direction of movement, transversely to the track, will result in withdrawal of the slide bar from locking engagement during the action of the first cam slot 61 upon the portions 58 of the pin. It will maintain the slide bar in non-locking position while the pin lies within the straight portions 60 of the slots and there will be relocking movement of the slide bar in the opposite direction at the other end of the continued movement of the plates 43 and 44 when the pin engages with the other cam slots 62. This is of course true of the movement in the reverse direction in that there will be corresponding unlocking, maintenance in unlocked position, and locking by the slide bar.

The top and bottom plates 51 and 52 are provided with mating slots or grooves 63 comprising central portions approximately transverse to the track, at 64 and end turned portions extending reversely at opposite ends 130

65, 66 with cam surfaces 67, 68 providing guides for the ends 69' of pin 69 carrying the combined sleeves and rollers 70.

The pin upon the end of rod 31 merely forms the means which I have illustrated by which the rod is effectively connected with the cams and guiding and driving surfaces which control its operation. I recognize that other constructions or projections of or upon the rod 31 would accomplish the same result if so formed and proportioned as to coöperate with the relatively fixed and movable members. In the claims I have, therefore, in some instances included some coöperative formation of the end of the rod 31 as part of the rod itself without specific designation, and where I refer to a pin thereon, I desire to include all mechanical equivalents therefor or thereof.

Between the ends 69 these rollers lie within mating slots 71 in the transversely movable plates 43 and 44. These slots 71 comprise approximately transverse end portions 72 and 73, out of line with each other, and an intermediate connecting portion 74, providing edges 75, 76 for engagement with the rollers under certain circumstances to move them bodily in one direction or the other within the nearly transverse portions 64 of the slots 63. The word transverse is used with reference to the length of the track. The rollers 70 act as spacing sleeves to hold the eye end 77 of switch rod or switch-operating rod 31 in position vertically and the pin 69 passes through this eye so that the movement of the rollers 70 and pin 69 transversely shall result in movement of the switch.

Starting with the plates 43 and 44 in the position shown in the drawings it will be seen that initial movement of the plates will result in the pin 69 and its rollers 70 remaining stationary in space because of the engagement of the rollers with the edges 78 of slots 63 while the side movement is prevented by engagement with the edges 79 of slots 72. The two movable plates 43 and 44 meantime travel past the rollers while the cam slots 61 are withdrawing the slide bar from its initial locking position and until the rollers engage with the edges 80 of slots 71 at approximately the same time as the portions 58 of the slide bar pin reach the straight portions 60 of the slots 59. The middle portions 74 of the slots 71 now permit and their edges 80 assist the rollers 70 to move into the portions 64 of the slots 63, but the edges 81 of the slots 64 prevent the rollers from moving far enough to pass within the ends 73 of the slots 71, with the result that the edges 75 of slots 71 engage with the rollers and drive them with their pin and the switch operating rod transversely of the track throughout the entire switch-throwing movement while the slide

bar pin is held in the straight portions 60 of the slots 59. It will thus be seen that direct transverse switch throwing movement is effected without cam operation of any member for any purpose during this movement, and without any movement of the slide bar, applying the full and direct force of the switch-throwing lever to the throwing of the switch during this movement. When the end of the switch throwing movement has been reached, the edges 68 of slots 63 guide the rollers into the portions 66 of these slots, and the portions 73 of the slots 71. As soon as the rollers 70 enter the end branches 65, any tendency to move in the reverse direction is taken up by the fixed frame by engagement with edges 78 which afford a definite bar against such movement and relieve the operating mechanism from all further strain from switch operating parts. The plates 43 and 44 continue their movement without any strain upon or from the switch, while the slide bar is thrown by slots 62 and the rollers 70 remain within slots 73. In the reverse movement of the plates 43 and 44 it will be seen that the unlocking movement takes place while the plates 43 and 44 are moving but not carrying the rollers 70 before the switch operating pin 69 has been freed from fixed support against edges 82 and without switch movement, and that the cam surfaces 83 of slots 71 guide the rollers 70 into line with the portions 64 of slots 63 so that the edges 76 shall drive the rollers and hence throw the switch as soon as the unlocking movement has been completed and the slide bar pin lies within the straight part 60. During this time there can be no movement of the bar. At the end of the stroke the rollers 70 are guided into the ends 72 of slots 71 and travel in these straight portions of the slots 71 while the slide bar is moved to the position shown. At this end also the switch is held in position, by engagement of rollers 70 with fixed edges 78.

The connecting member 46 can be inserted at either end of the plates 43 and 44 so that the switch can be operated from either side of the track with the result that my structure is of equal use for any position or movement of switch. The bars or rods 27 and 30 can be of any desired length.

The top plate 54 is a cover plate merely, in order that the slots may be cut freely through the plate and yet be kept clean and be protected from interference. It also holds the pins in place.

It will be evident that my invention has been illustrated and described in connection with a form of slide locking bar construction, which is considered desirable, but which is not the only one at present known or used and that my invention can be applied to any slide bar locking operation,

using slots such as those shown at 60, 61 and 62 where the movement of the slide bar is continuous from one locked position to the other through an unlocked intermediate 5 position.

It will be evident that other constructions of relatively fixed locking surfaces and intermediate guiding devices for controlling rod 31 may be supplied and that other means 10 for effecting direct driving engagement between it and rod 30 with locking of the rod 31 with its locking devices and subsequent relative movement between the two rods may be had within the scope of my invention.

15 It is evident that other means of slide bar operation, may be used in connection with my invention and that changes in the accessory parts, as well as in the form of application of my invention itself, may be 20 made use of without departing from the spirit and scope of my invention. It will be evident also that my invention may be applied to power switch operation with advantage in ease and reliability of operation.

25 What I claim as new and desire to secure by Letters Patent is:—

1. In a device of the character stated, switch points, a switch-operating rod co-operating therewith, extending at an angle 30 with the points and provided with a projection, a fixed guide for the projection substantially parallel with the rod, locking walls for the projection transverse to the rod and in proximity to the ends respectively of 35 the guide, means effective by reason of movement of the projection with the points for diverting it laterally with respect to the rod length from the guide against a locking wall and a driving member movable in the direction 40 of the length of the switch-operating rod and having abutments engaging the projection to drive it along the guide, and co-operating with the means for diverting the projection to seat the latter against a locking wall.

45 2. In a device of the character stated, switch points, a switch-operating rod extending transversely thereto and connected therewith, a projection from the rod, a fixed 50 member having co-operating walls at an angle to each other, one a guiding wall extending in the direction of the length of the rod and another retaining it against movement in the direction of the length of the 55 guiding wall, a guide at the junction of the walls, diverting the projection from the direction of the length of the guiding wall against the retaining wall and means for giving the projection movement along the 60 guiding wall of the fixed member.

65 3. In a device of the character stated, switch points, a switch-operating rod connected therewith and at an angle thereto, a fixed member, co-operating parts upon the rod and fixed member, one comprising a pro-

jection and the other having a guide for the projection and a wall at an angle to the guide effective as an abutment co-operating with the projection for retaining the rod and fixed member against relative movement in the direction of the guide length and means 70 movable substantially parallel to the rod length provided with engaging edges for freeing the projection and abutment from locking engagement, and driving the rod 75 lengthwise of the guide.

4. In a device of the character stated, a switch, an operating rod therefor having a projection thereon, spaced guiding plates forming a guide for said rod projection 80 guiding movement thereof parallel to the length of the rod, provided with a fixed lock therefor out of line with the guide, driving means between the plates engaging the projection to drive it within the guide and means maintained in operative relation to the guiding plates co-operating with the driving means to move the projection at an angle 85 to the guide into engagement with the lock.

5. In a device of the character stated, a switch, a fixed member and a movable member, both slotted, the one having a major slot adapted to act as a guide for movement in a direction transverse to the switch and smaller terminal slots lateral thereto on opposite sides thereof, and the other adapted to move in a straight line transverse to the switch and having terminal slots transverse to the switch, spaced laterally substantially the same as the extent between said lateral 95 slots, a connecting lateral slot, and a guide for the movable member, providing for its straight line movement, in combination with switch-operating means engaging the slots of both members and guiding means co-operating between the two members for causing the end of the switch-operating means to move parallel with the switch for engagement and disengagement with the 100 lateral slots.

110 6. In a device of the character stated, switch points, a rod movable therewith at an angle thereto and carrying a pin, a plate fixed against movement transverse to the switch, having a slot therein for the pin, said slot extending in line with the rod, slots 115 communicating with said slot and at an angle thereto, providing locking walls and cam surfaces located at the junction of the slots and guiding the pin laterally with respect to the length of the rod in combination with a movable plate having communicating slots therein for said pin provided with driving walls and cam surfaces located at the junction of the slots and guiding the 120 pin laterally with respect to the length of the rod, whose walls engage with the pin to drive it in the main slot of the relatively fixed plate and against the cam surfaces of said relatively fixed plate to engage with the 125 pin.

130
